UNITED STATES PATENT OFFICE.

JOHN C. RALLS, OF LOS ANGELES, CALIFORNIA, ASSIGNOR OF ONE-FOURTH
TO EDWARD J. FLEMING AND ONE-FOURTH TO PAUL USSER, BOTH OF
LOS ANGELES, CALIFORNIA.

FUSE-HOLDER.

No. 851,997.

specification of Letters Patent.

Patented April 30, 1907.

Application filed August 8, 1904. Serial No. 219,374.

To all whom it may concern:

Be it known that I, JOHN C. RALLS, a citizen of the United States, residing at Los Angeles, in the county of Los Angeles and State of California, have invented a new and useful Improvement in Fuse-Holders, of which the following is a specification.

The primary object of this invention is to provide a fuse holder which can be more readily connected and disconnected than the ones now in use.

Another object of the invention is to improve the electric and mechanical efficiency of the connection.

Another object of the invention is to provide a fuse holder which is readily adaptable to different situations and uses.

The accompanying drawings illustrate the invention.

Figure 1 is a side elevation of the fuse holder. Fig. 2 is a longitudinal section thereof. Fig. 3 is a top plan. Fig. 4 is a transverse section on the line x^1-x^2 in Fig. 2. Fig. 5 is a detail of the upper end of the holder showing the manner of connecting the same to the wire. Fig. 6 is a side elevation of the holder showing a different form of connecting head thereon. Fig. 7 is a plan of Fig. 6. Fig. 8 is a longitudinal section, partly broken, of a modification. Fig. 9 is a general view showing the application of the invention where the fuse holder is at the side of the building to which telephone connection is made. Fig. 10 is a similar view showing the application of the invention to a telephone wire.

Referring to Figs. 1 to 5, 1 designates the body of the holder which is made tubular to receive the usual fuse device 2. This tube may be made of hard fiber or other suitable insulating material. At each end the tubular holder has a tubular extension 3 on which is secured a thimble or metallic end piece 4, serving as attaching means for the respective heads or connectors 5, 6, at the ends of the holder, each of said thimbles being screw-threaded to engage with the screw-threaded sockets 7 at the inner ends of said heads. Said heads 5, 6, form outer caps which give a smooth finish to the fuse holder and secure a good connection by gripping the terminals of the fuse between themselves and the thimbles 4. Said caps also inclose and protect the terminals. The lower head 6 may have the usual bore 8 and set-screw 9 for the attach-

ment of the "house" wire 22. The upper head 5 serves for attachment of the holder to the telephone or lead, said head having a groove or channel 10 in its upper end to receive said wire. I prefer to make the walls 60 of said groove in such manner that they can be upset or clenched over the wire and for this purpose they may be formed as flanges or ribs 11 extending upwardly from the end of the head parallel to one another and are of 65 sufficiently thin and of sufficiently malleable metal to enable them to be bent over the wire when it is placed in the groove, as shown in Fig. 5, the connection being then completed by solder, indicated at 12 in said figure. 70 This form of the invention is adapted to the cases where the fuse holder is to be suspended directly on or from the telephone wire 16 or from a horizontal lead, as indicated in Fig. 10. In cases where the connection is to be 75 made at the side of a house, as shown in Fig. 8, the form of head, as shown in Figs. 6 and 7, will be used, the wire-receiving groove 10 being formed in the edge of a flange or wing 13 projecting laterally from the head 5 and provided with malleable extensions 11 to form 80 said groove. The wire 18, in this case extending vertically, will be placed in said groove and the malleable walls 11 will be clenched thereon and soldered. 85

The connection described can be quickly made and is mechanically of sufficient strength to prevent accidental rupture, while the solder can be easily applied to all parts of the joint, insuring perfect electrical connection, which cannot always be secured where the wire is passed through a perforation in the head. 90

It will be seen that after the malleable walls 11 which extend from head 5 have been 95 clenched upon the line wire, the body portion of the fuse holder may be unscrewed from or screwed into said head 5 to renew the fuse wire without disturbing the connection of head 5 with the line wire. This is an advantage not possessed heretofore, so far as I am aware, by fuse-holders adapted for use in connection with telephone or telegraph wires. By this invention the use of threaded nuts, exposed to the weather where they quickly 100 become rust-tight, is avoided. The threaded sockets 7 are protected from exposure to moisture by the body 1 against the end of which they abut, and the heads 5 and 6 in which they are inclosed. 105

In using the holder, the heads are unscrewed, the fuse inserted with its metallic terminals 17 projecting from each end, said terminals being then turned down over the 5 ends of the metallic thimbles 4 and clamped thereon by screwing on the heads 5 and 6. In order to insure good connection it is desirable to round the opposing faces of the thimble 4 and the socket 7. The heads or 10 connections 5, 6, not only serve as clamping means to bind the terminals of the fuse against the thimbles 4, but also serve to 15 close and protect said terminals.

The thimbles 4 may be fastened on the extensions 3 of the tubular body 1 of the holder in any suitable way, being, for example, simply forced thereon with a drive fit, but in some cases it is preferable to provide each 20 thimble with an extension or flange 19 (see Fig. 8) embracing the end of the tubular body 1 and fastened thereto by a rivet or cross-pin 20.

What I claim is:—

1. An elongated fuse-holder provided at 25 each end with means for making connection with a wire, said means at one end of the fuse-holder consisting of flanges of malleable

metal adapted to coöperate to grip a single wire.

2. An elongated fuse-holder provided at 30 each end with means for making connection with a wire, said means at one end of the fuse-holder consisting of flanges of malleable metal, said flanges projecting in a direction longitudinal to the length of the fuse-holder 35 and being adapted to grip a single wire and suspend the fuse-holder therefrom.

3. A fuse-holder provided with a central insulating body having a tubular extension 3 at the end, an externally-threaded cap fastened to said extension and engaging against the end of said body, an internally-threaded head screwing onto said cap and also engaging against the head of said body to form a closure therearound, and means carried by 40 45 said head for connecting the same with a wire.

In testimony whereof, I have hereunto set my hand at Los Angeles California this 20th day of June 1904:

JOHN C. RALLS.

In presence of—

FREDERICK O. LYON,
RILLA ROBERTS.
